CARL F. GOUDY, OF FLUSHING, NEW YORK, ASSIGNOR TO FACENT ELECTRIC COMPANY, INC., OF NEW YORK, N. Y., A CORPORATION OF NEW YORK

SPEAKER UNIT

Application filed April 19, 1928. Serial No. 271,152.

Special objects of the present invention are to provide an operating unit for loud speakers and the like, which will be powerful in its operation, and at the same time re-produce 5 faithfully, without distortion, which can be readily assembled and properly adjusted, and which will be particularly efficient electrically and magnetically.

The various novel features of construction, 10 combination and relations of parts by which the foregoing and other desirable objects are attained are set forth in the following specification.

The drawing accompanying and forming 15 part of the specification illustrates one practical commercial embodiment of the invention, but it should be understood that the structure may be modified and changed without departure from the true scope of the invention as hereinafter set forth and particularly claimed.

Fig. 1 is a plan view of the complete unit; Fig. 2 is a sectional view of the same as on 20 substantially the plane of line 2—2 of Fig. 1; Fig. 3 is an end view of the unit with one side of the same shown partly in section; Fig. 4 is a detail perspective view of the armature having the integral mounting wings; Fig. 5 is a detail perspective view of one of 25 the pole pieces.

The magnet of the unit designated 7 is shown as of the usual prominent horse-shoe type, but differs from the magnets customarily employed in that it is faced off on one side 30 to provide accurately finished smooth flat seats 8 for the pole pieces, and in that these flat pole tips are continuous and imperforate. The pole pieces 9 similarly have smooth finished flat imperforate faces 10 overlying and 35 fitting as absolutely as possible the flat polar seats on the tips of the magnets. By this construction, drilling or punching of the magnet or pole pieces are eliminated, and continuous complete joints are made between the 40 magnets and pole pieces eliminating magnetic losses.

For holding the pole pieces in place, a 45 clamp construction is provided shown in the form of a nonmagnetic bridge piece 11 over- standing the pole pieces, and a non-magnetic

clamp bar 12 of a rigid channel cross-section bridging the pole tips at the opposite side of the magnet, these two bridging members being firmly drawn together by the through screws 13 and 14.

The pole pieces are forked at their inner ends as indicated in Fig. 5 to provide polar projections 15 for acting on opposite ends of the armature and wide spaces 16 between such projections for the magnetic coils and narrower spaces 17 for passage of the clamp bolts 13. The polar projections 15 are shown as tapered down at 18 for the purpose of concentrating the magnetic flux.

The armature is designated 19, and the 6 same is shown as a substantially rectangular cross-section bar substantially the same width as the polar projections, and as long enough to bridge the forks of the pole pieces, and to provide a short thinned extension 20 to which 70 the pin or rod 21 is attached as by being driven fixedly thereinto. The outer end of the pin 21 is soldered, or otherwise suitably secured as shown at 22 in Fig. 3 in the channeled portion of a spring strip 23, which is 75 secured by an integral spring hinge 24 and screw 25 to a mounting post 26. This spring supported member 23 has attached to it the drive rod 27, which connects with the cone or other sound wave creating member.

Another special and important feature of the armature is that it is flexibly and resiliently mounted by means of integral side wings 28 springing from opposite sides of the same and flattened down as indicated in 85 Fig. 4 to form spring supports. In practice, the armature member is usually blanked out of soft magnetic stock in a single piece with integral protuberances at opposite sides of the bar portion of the same, and then these 90 protuberances are cold swaged to extend, flatten, and at the same time harden them to a sufficient extent to give them the desired spring quality, all this being effected without hardening the main bar portion of the armature.

The armature is mounted by gripping the side wings of the same, one in a clamp carried by the bridge or clamp member 11, and the other in a similar clamp carried by a mem- 100

ber 29 lying between the legs of the magnet and secured in opposition to the member 11 by nuts 30 on the clamp screws 13. The two armature clamps are of similar construction, and consist in each instance of a set screw 31, bearing on a shim 32, engaging the side wing, the latter extending into a seat in the form of a slot 33 in the supporting member. These shims, it will be observed, provide wide gripping surfaces bearing flat on the side wings, overcoming any tendency to rattle, and serving to prevent the screws as they are tightened from exerting a twisting tendency on the armature wings.

15 The magnet winding is shown as made in two sections in the form of flat coils 34 at opposite sides of the side wings, and surrounding the end portions of the armature bar. The terminals for this winding are 20 shown in the form of binding posts 35, Fig. 2 entered into open ended slots 36 in opposing flanges on the two members 11 and 29, and held tightly therein by the nuts 37. This construction permits of the binding posts 25 being slid into place in these slots, and then secured by simply tightening screws 37.

The two members 11 and 29 are in themselves in the nature of a clamp gripping the opposite sides of the pole pieces as shown 30 in Fig. 3 and enlarged as a more or less globular housing enclosing the magnetic winding, armature and polar projections. To more firmly secure the two parts of this housing together, the two through screws 38 35 are shown connecting the housing parts at one edge, and at the opposite edge these housing parts are indicated as held together by a cap screw 39 engaging over the companion tubular threaded extensions 40 of the two members. The slots 36 for the binding posts provide a cut-out portion at the top giving access to one end of the armature, and the pole tips cooperating therewith 40 and the tubular projections 40, when the cap screw 39 is removed, provide access to the 45 opposite end of the armature and the co-acting pole tips. Thus, a "feeler" or gage may be inserted at either end of the armature to 50 facilitate setting the parts in proper relation. The two members 11 and 29 of the coil housing are shown as having notches 41 positioning the coils and holding them properly 55 spaced from the armature and its supporting wings.

It will be seen that with the construction disclosed, the coil housing can be put together with the coils, the armature and the pole pieces all in place therein, and these 60 parts can all be properly set and adjusted as a separate assembly, which when complete and in proper working order can be applied as a unit to the magnet. The cost of the magnet is materially reduced by avoiding 65 any requirement to drill or machine the same,

and at the same time, the magnetic qualities are improved.

The armature is produced in a single piece without soldering or other jointing operations, the bar section being left of soft magnetic material and the windings being sufficiently hardened to resiliently support and give the desired tension to the armature.

What is claimed is:

1. A speaker unit comprising a permanent magnet having the polar portions of the same smoothly surfaced on one side and imperforate to provide accurate continuous pole seats, pole pieces having correspondingly smoothly finished continuous surfaces engaged with said pole seats and clamp means securing said pole pieces on said pole seats without passage of any fastenings through the permanent magnet, said clamping means including a coil housing bridging the pole pieces and a magnet winding in said housing. 75

2. A speaker unit comprising a permanent magnet having the polar portions of the same smoothly surfaced on one side and imperforate to provide accurate continuous pole seats, pole pieces having correspondingly smoothly finished continuous surfaces engaged with said pole seats and clamp means securing said pole pieces on said pole seats without passage of any fastenings through 90 the permanent magnet, said clamping means including a clamp structure securing the pole pieces in properly associated relation independently of any means holding the pole pieces to the magnet. 95

3. A speaker unit comprising a permanent magnet having the polar portions of the same smoothly surfaced on one side and imperforate to provide accurate continuous pole seats, pole pieces having correspondingly smoothly finished continuous surfaces engaged with said pole seats and clamp means securing said pole pieces on said pole seats without passage of any fastenings through the permanent magnet, said clamping means including a two-part coil housing, a magnet winding in said coil housing, an armature in the coil housing, the parts of said coil housing clamping the pole pieces and the winding in properly associated relation, and further having means for mounting the armature in proper relation to the winding and to the pole pieces. 105 110

4. In a device of the character disclosed, a clamp structure, cooperating pole pieces held in adjusted relation with said clamp structure, an armature for said pole pieces mounted in said clamp structure and positioned thereby in proper relation to the pole pieces, a magnet winding for said armature mounted in proper relation thereto in the clamp structure, a permanent magnet and means for securing the clamp structure with the parts thereby held in adjusted associated relation to the magnet as a single assembly unit. 120 125 130

5. In a device of the character disclosed, a clamp structure, cooperating pole pieces held in adjusted relation with said clamp structure, an armature for said pole pieces mounted in said clamp structure and positioned thereby in proper relation to the pole pieces, a magnet winding for said armature mounted in proper relation thereto in the clamp structure, a permanent magnet and means for securing the clamp structure with the parts thereby held in adjusted associated relation to the magnet as a single assembly unit, said latter means comprising a second clamp structure including in part portions of the first clamp structure. 70
- 10 6. In a device of the character disclosed, a permanent magnet, a two-part clamp, pole pieces for the magnet secured in adjustable relation between the members of said clamp, an armature for said pole pieces, securing means carried by the members of the clamp for mounting said armature in adjustable relation to the pole pieces, a winding for the armature held positioned in proper relation thereto between the members of the clamp, and means for binding the assembled clamp structure in adjustable relation to the permanent magnet. 85
- 15 7. In a device of the character disclosed, a permanent magnet, a two-part clamp, pole pieces for the magnet secured in adjustable relation between the members of said clamp, an armature for said pole pieces, securing means carried by the members of the clamp for mounting said armature in adjustable relation to the pole pieces, a winding for the armature held positioned in proper relation thereto between the members of the clamp, and means for binding the assembled clamp structure in adjustable relation to the permanent magnet. 90
- 20 8. In a device of the character disclosed, a two-part coil housing, pole pieces adjustably clamped between the members of said housing, an armature mounted in said housing in cooperative relation to said pole pieces, means for securing the members of the housing together at one end of the armature, and a cap screw for securing the members of the housing together at the opposite end of the armature and adapted on removal to expose said 95
- 25 opposite end of the armature. 100
- 30 9. In a device of the character disclosed, a magnet having pole pieces, an armature for cooperation with said pole pieces, said armature having side wings by which the same is supported and clamps for adjustably securing said side wings, said clamps including shims bearing on the side wings and set screws engaging said shims. 105
- 35 10. The method of forming an armature and an elastic mounting therefor, which comprises blanking out an armature with integral protuberances at opposite sides of the same and then swaging said protuberances to harden and thin the same into elastic side wings. 110
- 40 11. The method of forming an armature and an elastic mounting therefor, which comprises blanking out an armature with an integral protuberance and then swaging said protuberance to relatively harden and thin the same into an elastic supporting wing. 115
- 45 12. As a new article of manufacture, a solid continuous one piece armature and mounting, comprising an armature bar of soft iron having integral rolled, compacted, so thinned, springy wing projections. 120
- 50 13. As a new article of manufacture, a continuous solid, one-piece armature and spring mount therefor, comprising an armature bar of soft iron having an integral compacted and thinned springy projection. 125
- 55 14. In a device of the character disclosed, a clamp structure, cooperating pole pieces held in adjusted relation with said clamp structure, an armature for said pole pieces supported by the clamp structure in position to properly cooperate with the pole pieces, a coil carried by the clamp structure in cooperative relation to the armature, a magnet and means for securing said clamp structure with the parts thereby held in adjusted associated relation to the magnet as a single complete assembly unit. 130
- 60 15. In a device of the character disclosed, a magnet having the polar portions of the same smoothly surfaced on the front face and imperforate to provide smooth, accurate, continuous pole faces, pole pieces having correspondingly smoothly finished continuous surfaces engaged with the front pole faces of the magnet, a clamp bar overstanding said pole faces, a clamp bar overstanding the back faces of the magnet and clamp bolts extending between said clamp bars at the front and back faces of the magnet to thereby solidly clamp the pole pieces over the front face of the magnet. 135
- 65 16. In a device of the character disclosed, a magnet having the polar portions of the same smoothly surfaced on the front face and imperforate to provide smooth, accurate, continuous pole faces, pole pieces having correspondingly smoothly finished continuous surfaces engaged with the front pole faces of the magnet, a clamp bar overstanding said pole faces, a clamp bar overstanding the back faces of the magnet, clamp bolts extending between said clamp bars at the front and back faces of the magnet to thereby solidly clamp the pole pieces over the front face of the magnet and a securing member associated with said front clamp member for securing the pole pieces in spaced relation prior to the mounting of the same to the magnet. 140
- 70 17. In a device of the character disclosed, 145

a magnet having the polar portions of the same smoothly surfaced on the front face and imperforate to provide smooth, accurate, continuous pole faces, pole pieces having correspondingly smoothly finished continuous surfaces engaged with the front pole faces of the magnet, a clamp bar overstanding said pole faces, a clamp bar overstanding the back faces of the magnet, clamp bolts extending between said clamp bars at the front and back faces of the magnet to thereby solidly clamp the pole pieces over the front face of the magnet, the pole pieces being forked to provide spaced arms and the clamp bolts aforesaid extending through the spaces between said arms of the pole pieces.

In testimony whereof I affix my signature.
CARL F. GOUDY.
